UNITED STATES PATENT OFFICE.

JUAN G. HOLGUIN BURBOA, OF HERMOSILLO, MEXICO.

TYPE-WRITING MACHINE.

1,089,689.

Specification of Letters Patent. Patented Mar. 10, 1914.

Application filed February 13, 1913. Serial No. 748,219.

To all whom it may concern:

Be it known that I, JUAN G. HOLGUIN BURBOA, a citizen of the Republic of Mexico, residing at Hermosillo, in the county of 5 Hermosillo and State of Sonora, Mexico, have invented a new and useful Type-Writing Machine, of which the following is a specification.

The present invention relates to improvements in typewriting machines, the primary 10 object of the present invention being the provision of a machine so constructed and arranged as to permit of the operation thereof to record coincidently with speech without the necessity of transcribing, the construction permitting the writing of a single or a plurality of letters simultaneously, there being provided a plurality of cases of 15 type keys, each case of which is constructed to engage the platen and its individual presentation spaced thereupon so that the one type of one case will not interfere with the type of the other case.

A further object of the present invention 20 is the provision of keys so disposed as to be comfortably manipulated by both hands of the operator, there being preferably three series of keys to each hand and six keys to a series, while to provide extra means for 25 operating the different mechanisms of the typewriting machine, wrist actuated keys are also provided one for each hand.

A still further object of the present invention is the provision of means controlled 30 by one key or any combination of keys, whereby with a single set or number of keys less than the number of letters of the alphabet, as for instance, six keys, a full alphabet may be controlled and actuated, the 35 combination of the respective keys or a single key of each series operating the distributor device or in other words, the selector which will cause the proper actuation of the 40 selected key to type presentation position 45 upon the platen.

A still further object of the present invention is the provision of a plurality of selectors one to each hand set of keys and one to each wrist set of keys, a fourth selector 50 being provided and controlled through the various combinations of both finger actuated sets of keys to perform various operations as regards the spacing of the platen, the rotation thereof and the movement during the writing of the type or the return of 55 the carriage to initial position.

In general, the present typewriting machine, consists of key and wrist actuated means whereby the various types of the different cases are placed in platen engaging 60 position to cause the presentation thereto of a single type or in the present instance, four type, so that short words, portions of words, or abbreviations may be written simultaneously, there being provided automatic spacing mechanisms controlled due to the number of type actuated so that the platen will be rotated the necessary number of spaces for presenting, in type presentation position, a clean sheet. The rotary platen 70 is so mounted as to be moved normally vertical from the top to the bottom of the page by the spring actuating mechanism, the same being returned from the top to the bottom of the page for the new page by an automatically actuated mechanism and against the tension of a spring. The platen also rotates in the same sense when line writing and when beginning a new line. The paper which receives the upper end of the type is 80 disposed within the hollow platen and wound from one reel to another so that the action of the paper from one page to another is controlled from the key board and automatically stopped at the desired point so that 85 at the instant of the movement of the platen from its uppermost to its lowermost position, a new sheet of paper to constitute a new page will be placed upon the platen in a position for receiving the beginning of the 90 new page. Other means for limiting the marginal position of the platen and for tabulating is provided, the same being controlled from the key board. A back spacing device is also provided in connection with the 95 marginal device so that the platen may be moved rearwardly the desired number of spaces for back spacing.

The control for the present typewriting machine is preferably pneumatic, but it is evident as will presently appear that the pneumatic devices may be displaced and electro magnets controlled through any form of generator or battery may be provided.

With the foregoing and other objects in view which will appear as the description proceeds, the invention resides in the combination and arrangement of parts and in the details of construction hereinafter described and claimed, it being understood that 105 changes in the precise embodiment of the invention herein disclosed can be made with-

in the scope of what is claimed without departing from the spirit of the invention.

In the drawings—Figure 1 is a perspective view of the main casing of the typewriter, the necessary supporting stand and motor operating mechanism being eliminated. Fig. 2 is a diagrammatic perspective and sectional view taken from the rear showing the main motor and the control mechanism for rotating and vertically moving the platen. Fig. 3 is a cross sectional view through the main casing at a point below the type basket showing the position of the various selectors, the operating motors and the platen. Fig. 4 is a central vertical cross sectional view through the casing with a greater portion of the type basket removed. Fig. 5 is a perspective view of one of the selectors *per se*. Figs. 6 and 7 are detail 10 plan views of one of the rotatable disks of the selector, Fig. 6 showing a means for increasing the number of type actuated by a single disk. Fig. 8 is a diagrammatic view illustrating the action of a single type bar and its key control. Fig. 9 is a top plan view of one of the oscillatory disks of one of the selectors showing its controlling mechanism. Fig. 8^a is a diagrammatic sectional view of the selector as shown in Fig. 5 to illustrate the actuation of the same to 15 select the desired mechanism to be operated thereby. Fig. 9^a is a diagrammatic plan view of the key controlled action of one of the oscillatory disks of the selector. Fig. 10 is a diagrammatic view in elevation of a portion of the type writer adjacent the type basket and platen showing the method of actuating the movable section of the basket. Fig. 11 is a diagrammatic plan view of the 20 various mechanisms for controlling the rotation of the platen, the space dial, the tabulator mechanism, and the ribbon feed. Fig. 12 is a diagrammatic view illustrating the method of imprinting four types simultaneously upon the platen and showing the relative position of the various type cases of the basket. Figs. 13, 14, 15, 16, 17 and 18 are views, illustrating the construction and arrangement of the motors and motor controls, whereby the various mechanisms illustrated in Fig. 11 are actuated selectively. Figs. 19, 20, 20^a and 21 are detail views illustrating the preferred form of escapement device used in connection with the letter spacing of the platen and also in connection with the escapement device used in connection with the elevation of the platen. Figs. 22 and 23 are detail views showing the interior and adjacent portions of the 25 low platen and the method for controlling the placing of the paper upon the exterior of the platen. Fig. 24 is a detail plan view illustrating the marginal and tabulator device. Fig. 25 is a detail view of the 30 leasing pawl and operating mechanism for 65

controlling the marginal stop of the marginal and tabulator device as shown in Fig. 24. Fig. 26 is a detail perspective view illustrating the position and construction of one key of each of the three finger controlled sets. Fig. 27 is a diagrammatic perspective view of the ribbon control and shifting device. Fig. 28 is a plan view of the type end of a type bar of the removable section of the type basket. 70

In describing the present invention, the various mechanisms will be taken up in turn and under the following sub-topics: The frame and main motor; type basket and control mechanism; platen and carriage; platen spacing and back spacing mechanism; paper control; ribbon mechanism; marginal stop and tabulator device; type basket actuating mechanism; and signal device. 75

Frame and main motor.—Referring to the drawings, the numeral 1 designates the frame and casing, said casing being provided with the forward extension at the lower edge thereof provided with the oppositely inclined faces 3 and 4 which provide a comfortable support for the respective left and right hands of the operator who sits to face the casing with his left hand upon the inclined portion 3 and the right hand upon the inclined portion 4. Provided in the front of the casing is the aperture 5, whereby the various type bars, as will presently appear, may be readily had access to for cleaning and also whereby the visible writing upon the platen 13 may be readily seen at a glance. 90

The upper forward end of the casing 1 is cut away as at 7, while the extreme rear portion is cut away, as at 6, to provide for the necessary movement of the vertically movable platen 13, the detail of which will be set forth later on. Mounted in the rear of the casing, as clearly shown in Figs. 2 and 3 are the two pneumatic motors 8 and 8', 105 each one of which is actuated by the respective feet of the operator through the flexible connections 9, each of which is disposed over the two pulleys 10 and 11 and is connected below the casing to a treadle (not 110 shown). By this means the respective motors 8 and 8' are operated alternately and being of a similar structure to the pneumatic structures used in connection with piano players and other suction machines, will 115 automatically operate to create the necessary vacuum within the vacuum chamber 12 which is also supported and carried within the casing 1. 120

Type basket and control mechanism.—125 The platen 13 is mounted for movement vertically up and down at the rear of the machine, and the detail of such actuating mechanism will be set forth later on, while the type basket which as shown in Fig. 12, is 130

composed of the respective sections A, B, C and D, the sections B, C and D being stationary and disposed within the arc of a circle so that the respective type bars will be properly presented, while the type bars of the section A constitute a movable section, the construction of which will be set forth later on, and is controlled to present a single type at a time, when desired.

- 10 Each type bar of the respective cases, is controlled and constructed as shown in Fig. 8, the type bar 14 being pivotally mounted in the supporting means 15, and having its short arm 16 connected by a link 17, whose 15 other end is connected to the movable section 18 of the bellows 19, the same constituting a vacuum actuated motor for actuating the type bar 14 to present its type 14^a in type presentation position upon the 20 platen 13.

In the machine herein illustrated, each of the respective sections A, B, C and D of the type basket are controlled by the various selector devices 20, 20', 20^a and 20^b, these 25 devices herein as described and known as a selector, and all of which are constructed similarly, so that the description of one will suffice for the description for all.

The detail structure of the selector is 30 clearly shown in Figs. 7, 8, 9, 8^a and 9^a, and consists primarily of the lower disk 21 which constitutes a vacuum chamber 22, as clearly illustrated in Fig. 8^a. This chamber 22 has a nipple 23 which has connected 35 thereto the flexible tubing 24 led from the vacuum chamber 12, and as said vacuum chamber 12 is, as before stated, connected to the respective motors 8—8', the vacuum is created therewithin and consequently 40 through the tube 24 in the chamber 22. This chamber 22 is provided with a plurality of ports or ducts 25 and also has rigidly connected thereto, the outer disk 26, which constitutes with the disk 21, the supporting 45 medium for the plurality of oscillatory disks a, b, c, d, e and f. The outer disk 26, as clearly shown, is provided with a plurality of ports 26', whose mouths each have connected therein the nipple 27, said nipple 27 50 having led thereaway from the tube 28, which provides a means whereby the vacuum effect produced, as will presently appear, will actuate its selected motor 19 to cause the presentation of the selected type 14^a. The 55 various oscillatory disks or rings as a, are mounted properly for individual movement between the disks 21 and 26, and each is provided with a plurality of apertures 53 and exhaust ports 54, the apertures 53 being 60 disposed to be placed in registration with the respective apertures 53 of the adjacent oscillatory disks so as to provide, by the action of the disk, as f, Fig. 8^a, or by the combined action of two or more of the disks 65 as a, registering conduits from one of the

ports 25 of the vacuum casing 22 to one of the ports 26' of the plate 26, this action causing the diaphragm 45 carried by the support 43 and having the casing 44 to be inwardly flexed to actuate the valve stem 70 75 46 carrying the valve 47 and against the spring 48, opening the port of the casing 21^a and closing the exhaust or outlet port 50, all as clearly shown in Figs. 8 and 8^a. This action will direct the vacuum effect from the chamber 12 through the tube 51 which is connected to nipple 52 of the casing 21 to operate the selected motor 19 and cause the proper presentation of the type 14^a. Upon the non-registration of the selected disk a, b, c, d, e or f, or any combination of them so as to cause the intersecting of any of the channels formed by the various ports 25, 53 and 26', the valve stem 46 will be released due to the suction action upon the diaphragm 45 being released, so that the spring 48 will move the valve 47 to open the port 50 and close the port of the chamber 21^a, this action permitting the spring of the motor 19, due to the opening of the port 50 to 90 the atmosphere, to assume its expanded position so that the type bar 14 will be moved to its normal position. The type bars may be constructed to be returned by springs or by gravity and still be within the scope of 95 the present invention.

In order that the respective oscillatory disks such as a may be operated selectively to produce the desired combination and operate the selected type bar 14, or cause the 100 actuation of the desired mechanisms as will presently appear, each disk is provided with an apertured arm or lug 29, projecting radially therefrom and connected by a link 30 to the free end of a link 31, the link 31 being pivotally mounted at its other end to a fixed support 32 disposed conveniently with relation to its respective selector. Led from the connection between the two links 30 and 31 is an operating means 33, which may be a flexible cord or any rod which carries thereupon the disk 35 to coact with the stationary disk 34 to extend the spring 36 so that the oscillatory disk may be returned to its normal position upon the release of the manually controlled selecting key 39—39' or 39^a. The detail of this structure is clearly shown in Figs. 8, 9 and 26, the connection 33 being preferably connected to an arm 37 of a bail 38 for operating 115 the respective selectors 20 and 20' or to a lever 42 for oscillating the disks of the selector 20^a. The respective levers 42 are controlled through the laterally disposed levers 40 which are disposed as shown in Figs. 3 and 4 below the respective bifurcated ends 41 of the key bars 39, 39' and 39^a of the respective right and left hand sets of keys of 120 the machine.

As clearly shown in Fig. 3, there are three 130

of these levers 40 to each right and left hand, and there are preferably as illustrated at the left in Fig. 3, six keys 39, which constitute the disk control of the oscillatory disks of the respective selectors 20 and 20', which as will presently appear control primarily the actuation of the various type bars 14 of the different cases of type.

- By the arrangement and construction of 10 the various key levers 38, 39 and 40, in combination with the connections 33 and levers 42, different combinations are effected by the use of one key or any number of keys therewith to cause the desired oscillation of the 15 respective disks *a*, *b*, *c*, *d*, *e* and *f*, of the respective selectors 20-20' so that the selected type bar will be actuated to present the type at the desired point upon the paper upon the platen 13. As for instance, the 20 actuation of the single or any combination of the keys 39 at the left hand side of the machine will actuate the selected disk or disks of the selector 20, which in turn through the respective selected motor 19 25 controlled thereby, will actuate the selected type of the sectional and slideable section A of the basket, so that its type will be presented upon the platen 13 at the extreme left as viewed in the diagram Fig. 12. Each one 30 of the respective type bars of the section A carries preferably three type, an upper and lower case consisting of the small and capital letters and the various marks used, as colon, semi-colon and accenting marks. 35 This section A, as will presently appear, is moved to present either one of the respective types to the platen, the small letters being positioned to coact in combination with the single type of the various type bars of 40 the sections or cases B, C and D so that under ordinary conditions one type of each case may be operated to present four types simultaneously to the presentation point of the platen 13. When a capital letter is used 45 of the case A, only the type of the cases B and C can be used while where a third type is used only the type of D can be used, the reason of this being clearly apparent from the description to follow later on.
- 50 In the same manner as the individual keys of a set of keys 39-39' or 39^a, can be combined to write one letter of the first or second case A-B, at the same time, by advancing some fingers more than the others, the 55 sets of keys 39, 39' and 39^a can be combined, and a combination of them, by means of the levers 40-42, through the selector 20^a, registers a letter of the third case C, simultaneously with those of cases A-B.
- 60 The selector 20^b consists only of two disks *a'-b'* and is used as a spacing selector, or for causing the writing of usually the most frequent letters of the alphabet, as for instance, *e* and *s*. These respective disks *a'* 65 and *b'* are controlled through the flexible

connections 33'-33^a operated by the respective disk actuated key levers 55-55' disposed at the forward corners of the inclined portions 3 and 4 of the casing and directly below each of the respective left and right wrists of the operator.

Platen and carriage.—The platen 13 is disposed for vertical movement instead of the usual horizontal movement for producing writing upon the top to the bottom of the page, while the same is rotated horizontally during the writing of a line, the same being actuated a space or a number of spaces at a time according to the number of type 70 that are presented to the platen through the actuation of the keys and combinations thereof.

A lower cross-bar 57 is connected by means of the two vertical rods 58 to the upper cross-bar 59, each of the rods 58 being 85 movable and journaled for vertical sliding movement within the stationary or fixed tubes 60 mounted properly within the casing, the axis 61 of the platen 13 being journaled in the cross-bars 57 and 59 for rotation while the bars or rods 58 are mounted within the tubes 60 for vertical movement, the said rods 58 and cross-bars 57 and 59 constituting the carriage for the platen and 90 bodily movable vertically.

In order to produce the necessary horizontal rotation of the platen 13 to present a new space for the presentation of a type thereto, after the actuation of the type bar controlling keys of the machine, the motors 100 62 and 63, which are of the suction bellows type, are provided, and have their control through the vacuum chamber 12 and the selector 20^a, one of the levers 42 being the control therefor, so that these motors 62-63 105 will be operated to operate the crank shaft 64 which is journaled in the respective bearings 65 and 66. As clearly shown in Fig. 2, there is keyed upon the crank shaft 64, a gear 67, which under normal conditions is 110 in mesh with the gear 68 carried upon the lower end of the oscillatory and rotatable shaft 69, this shaft 69 being journaled within the swiveled or swinging block 70 disposed between the spaced arms 71 of the 115 supporting lugs 72. The supporting lugs 72 are secured to one of the tubular supports 60 which constitutes one of the carriage guides. The shaft 69 being thus rotated, rotates the upper gear 73, which is at that time in mesh with the gear 74 upon the lower end of the vertical shaft 75, this vertical shaft 75 having keyed upon it the intermediate gear 76 for actuating the escapement 82, as will 120 presently appear, and the upper gear 77, 125 which constitutes the main operating gear for the rotation of the platen 13, the dial 202, and the marginal control 206, all as clearly shown in Fig. 11.

A gear 78 is in mesh at all times with the 130

gear 77 and transmits motion through the large gear 79 to the long gear 80 which is disposed vertically of the machine and in mesh at all times with the gear 81 connected to the platen 13 and its shaft 61 so that regardless of the position of the platen relatively to the casing in its vertical up and down movement, the gear 81 will cause the desired rotation of the platen to present a new space for the presentation thereto of the type. By reason of the fact that the lever 42 with the selector 20^a for actuating the motors 62 and 63 are operated at all times through one of the levers 40 controlled by any one of the keys 39, 39' or 39^a, the platen 13 will be rotated one space for each type, but should four type be presented as illustrated in Fig. 12, the motors 62 and 63 will be rotated to impart to the platen 13 a movement equal to five spaces which constitute the four spaces for each type and the extra space between the type for the next space to be printed.

In order to provide a means for indicating at a glance the position of the platen relatively to the type line being printed, a gear 200 is in mesh at all times with the gear 201 which actuates the dial 202 disposed at the forward upper edge of the machine and in ready view of the operator.

The control device for the respective motors 62 and 63 is clearly shown in Figs. 13, 14, 15, 16, 17 and 18, and includes the two stationary plates 301 and 302 which have mounted for oscillation therebetween, the controlling rotatory disk 303, the tubes being led from the vacuum chamber 12 to the ports of the disk 301 and to the motors 62 and 63 through the respective tubes 62' and 62'' and 63' and 63'' to the disk 302, the rotatory disk 303 being provided with the recessed portion, as clearly shown in Fig. 17, so as to cause the inter-linking or inter-communication between the respective tubes 62' or 62'', or 63' or 63'' to impart the necessary action to the movable bellows of the motors 62 and 63, respectively, and consequently cause the desired actuation of the shaft 64.

In order to operate the platen carriage to impart to it the necessary upward vertical movement, due to the line spacing and also to impart to it the descending vertical movement during the change from a written page to a new page, the shaft 69 must be swung so as to disengage the gear 73 from the gear 74 and the gear 68 from the gear 67, this being effected through the motor 83, controlled through the selector 20', said motor 83 being operably connected to the bell crank lever 84 which is connected to the sliding block 85 mounted upon the two spaced pins 86 of the support 72. This block 85 has the shaft 69 journaled therethrough and when moved by the motor 83, causes the

positioning of the gear 87 into mesh with the gear 88, so that the shaft 69 is rotated to actuate the gear 89, and as the bevel gear 89 is placed in mesh with the bevel gear 90, the shaft 91 journaled in the bearings 92 and carrying the gear or pinion 93 is rotated. This rotation controls the motion to the toothed rack 94 of the platen carriage, said rack being disposed between the cross-bars 57 and 59, and causes the platen carriage to be elevated the desired spaces, as for instance, one line, two lines or three lines, or will cause movement downwardly of the platen 13 from its highest to its lowest point upon the presentation of a new page and against the tension of the carriage actuating spring 56 (Fig. 11) which is of usual construction and is connected to normally elevate the carriage.

The escapement mechanism for permitting the movement of the carriage and platen due to the shifting from one line to the next and for varying spaces as for instance one, two and three spaces, consists of the toothed rack 95 carried at the opposite side of the platen to the rack 94, the same having in mesh therewith at all times, the gear 96 carried upon the swinging shaft 96', the block 97 being constructed and arranged according to the sliding block 85 for swinging the shaft 95 and placing the gear 96 into and out of engagement with the rack 95 according to the actuation of the motor 99 and consequently the desired spacing required. The block 100 is the swingingly journaled block for the shaft 96', while the escapement 101, shown at the right in Fig. 2 and which is constructed similarly to the escapement 82, is provided for actuating the shaft 96' or rather controlling the actuation thereof to permit the movement of the platen and carriage the desired and selected spacing distance from one line to the next.

In order to permit the upward and downward movement of the carriage, the adjustable marginal stop 102 with the pneumatic buffer 103 is provided to be engaged by the cross-bar 59 when the carriage is returned from its extreme upper to its lowermost position upon the presentation of a new page, while the adjustable marginal stop 104 and its projecting end 105 are provided to engage the lower cross-bar 57 of the carriage and thus limit the upward movement of the same. These two stops are adjustably mounted upon the guide rod 106 which is fixed to the frame of the machine so as to provide a rigid support therefor.

Platen spacing and back spacing mechanism.—In order that the platen, as before described, may be rotated a single space or up to five spaces in the present instance, an escapement device, as clearly illustrated in Figs. 19, 20 and 21 is provided, this escapement device also being similar to the device 130.

101 for controlling the vertical movement of the platen carriage, both of such devices being constructed for control from the key board and through the vacuum chamber 12. 5 The gear 76 in this instance as before stated, is geared to the rotatable casing 82' of the escapement device 82 and this casing is provided with the teeth 107 and the facial pins 108. A fixed frame 109 is provided with 10 the two parallel rods 110 upon which are slidably mounted the sleeves 111 which bodily carry the finger carriage 112, the fixed lug 113 being connected to one end of the carriage and having fast thereto, a pin 114, 15 which forms a journal for the points 115 of the respective tooth engaging fingers 116, 117 and 118, there being a single finger 116 formed integral with the lug 113, a plurality of four intermediate fingers 117, and a single flexible finger 118. This finger 118 is 20 provided with the flexing end 119, which is normally held co-extensive with the main body of the finger 118 by means of the spring 120. Each of the respective fingers 118 and 25 117 are provided with a pin 121, which overlaps the adjacent finger, as clearly shown in Fig. 20, so that the fixed finger 116 limits the movement of the respective fingers in the direction of the arrow Fig. 19 and consequently in a position for engaging the teeth 107 to lock the disk 82 against rotation. 30 The springs 119' are connected to the lugs 118' of the various movable fingers 117 and 118 to form a resilient means for permitting 35 the back stepping or back spacing of the disk 82 and consequently the platen 13 by means of the back spacing motor 129 which is provided with the flexing arm 130 connected by the pivoting lug 131 to the movable section 132 of the motor. 40 This operation is controlled from the key board to back space the disk 82 one space as desired.

In order to control the actuation of the carriage 112, the same being maintained in 45 its normal position by means of the spring 125, with the finger 119 in engagement with one of the teeth 107 to maintain the disk 82' in the desired position, and so as to bring one of the respective teeth 117 or the flexible 50 tooth 118 in engagement with one of the teeth 107 to permit of the movement of the disk 82' and consequently the platen 13 the desired number of spaces, the flexible connection or cord 122 is trained over the 55 rollers 123 and 124 and has one end connected to the carriage 112 to move the same against the tension of the spring 125, this structure being clearly illustrated in Figs. 20 and 21. This flexible connection 122 is 60 connected to the pivoted bail or lever 126, carried upon the shaft 127 within the casing, this bail or lever 126 being operably connected to the controlling members of the respective motors 128, there being five of these 65 motors each of a different magnitude of

movement, so as to control the relative movements of the lever 126 and consequently the difference of pull upon the cord 122 so as to present the selected one of the respective fingers 118, 117 or 116, to its respective tooth 107 of the dial 82' and thus consequently permit the necessary movement to the platen 13. By this means, it will be seen that the actuation of the selector 20', due to the movement of any one of the levers 42 will control 75 the actuation of any one of the motors 128, or any number thereof, so as to properly actuate the lever 126 and the respective fingers 118, 117 and 116, so that the escapement drum 82' will be permitted to move 80 the desired distance through its motor controls 62 and 63 heretofore described.

Paper control.—In a machine constructed for this character of work, it is desirable that the necessity of removing a finished page from the platen and the placing of a new page thereupon be dispensed with, and in order that an automatic means may be provided for placing upon the surface of the platen, at any desired time, a new sheet of 85 paper, and also provide a means for retaining the succeeding new sheet and also the sheet theretofore printed upon, the detail structure as shown in Figs. 22 and 23, is designed and employed. In this structure, the 90 platen 13 is hollow and is provided with the longitudinal slot 133 through one side thereof while journaled within the platen and substantially the full writing surface thereof, is the supply roll 134, and the winding 100 roll 136, the paper 135 being led from the supply roll 134 through the slot 133 around the exterior surface of the platen 13 and through the slot 133 to the winding roll 136. To cause the movement of the paper written 105 upon and the placing of a new sheet upon the exterior of the platen, a motor device, as clearly shown in Fig. 23, is provided. In doing this, the nipple 137 is connected by a 110 flexible tube to the vacuum chamber 12, and its duct is in communication with the duct 138 formed in the rod 58 and bridging member 59 of the carriage, the other terminal of the channel or duct 138 being in communication with the duct or channel 139 formed 115 in the upper end of the axle 61 of the platen 13. This structure is clearly shown in Fig. 22. Led from the nipple 140, formed upon the axle 61 is a tube 140', which is in communication with the control chamber J of 120 the bellows motor 141 these being of similar construction to those heretofore described. This mechanism is preferably controlled through one of the keys and the selector 20', so that the motor 141 is operated when it is 125 desired to shift the paper from a finished type written page to a new page. This is accomplished by means of the segmental arm 142 carried by the movable member of the motor 141, and the pin and slot connec- 130

tions 143 and 144 of said arm 142 to the operating link 145. This link 145 is connected to the pawl carrying arm 146, which is disposed to engage the ratchet teeth 147 normally held against retrograde movement by the arresting pawl 148, to thus rotate the large gear 149, which is in mesh with the small gear 150 of the roll 136.

The movement of the arm 142 and its pin 10 and slot connection is such as to impart the necessary rotation to the gear 149, for any number thereof that may be necessary to cause the paper to be moved the proper distance to wind the type written page within 15 the platen and upon the roll 136 to present a new page upon the surface of the platen 13. In order to provide a locking means for the paper while in type presentation position, a flexible cord 151 is connected to the 20 movable member of the motor 141, passing over the guide pulley 152 and through the spring limiting lug 153 to the brake shoe 154, the spring 155 being so disposed as to normally exert an outward pressure upon 25 the brake shoe 154 to wedge the same within the space 133 of the platen and against the sheet of paper at such point. It will thus be seen that the initial movement of the motor 144 will not affect the rotation of the 30 gear 149 and consequently the roll 136 until after the cord 151 has been actuated to remove the brake shoe 154 from engagement with the paper at the slot 133, thus allowing ample time for the paper to be released so 35 that the roll 136 may be operated to remove the type written sheet from the surface of the platen and present thereupon a new sheet.

In order to provide a pneumatic means 40 for stopping the actuation of the motor 141 when the type written page has been removed within the platen 13, the paper is perforated at intervals, such intervals being preferably the distance from the slots 156 formed in one wall of the slot 133 to the 45 adjacent wall of the slot 133, such perforations being thus presented at the proper time to the slot 156 of the channel 157. The slot 156 is extended the full length, or 50 any predetermined distance throughout the length of the slot 133, the same having its nipple 157 engageable with the release side of the valve and control casing J of the motor 141, so as to act in a similar manner to the release of the valve 47 of the devices 55 shown in Fig. 8^a, so that the motor 141 will be open to the air and will thus collapse and be stopped in its action as regards the rotation of the roll 136, the arm 142 being moved in the opposite direction so that the pawl 60 arm 146 will ride upon the teeth 147 without affecting the movement thereof but to be placed in a position for the next succeeding action or page changing.

In order that envelopes may be held upon 65 the present platen, the envelop clips E are

provided and are connected to the adjacent scale marked flanges F of the platen 13, as clearly shown in Fig. 22.

Ribbon mechanism.—The ribbon mechanism and the control therefor is clearly 70 shown in diagram in Fig. 27, the mechanism for operating the shaft 168 being shown in Figs. 2 and 11, and consisting of the motor 158, which is controlled at the actuation of any one or any combination of the keys 75 to properly feed the ribbon 176 to present a new portion thereof to each type presentation, said motor 158 having its movable member connected through the link 159 to the bell crank lever 160, whose hooked terminal 161 is operably connected to the carrying block 162 which is constructed similar to the block 85, and provides a means for tilting the shaft 163, which is rotatably mounted within the swinging block 164, as 80 clearly shown in Fig. 2. Keyed upon the shaft 163 is a gear 164', which operates the gear 165. This gear 165 has a pulley portion over which is trained the endless chain or cord 166, which is operably connected to 85 the sprocket wheel or pulley 167 keyed upon the rotatable and slidably mounted shaft 168, which constitutes the shifting shaft and power transmission shaft of the ribbon mechanism. Keyed upon this shaft 168 are 90 the two bevel pinions 170—171 and the manually controlling crank 169, which as clearly shown in Fig. 1 is disposed at the upper portion of the casing 1 in ready access to the operator.

A bevel gear 172 is disposed at the lower portion of the casing and is carried by the shaft 173 which has keyed upon its inner end the ribbon spool 174, the same being 95 provided with the arcuate slot 175 open to the periphery thereof for the seating therewithin of the ribbon carried shifting actuating pin 180, there being two pins one adjacent to each end of the ribbon 176 and disposed to assume the various positions as 100 shown in Fig. 27. The shaft 178 is provided with a bevel pinion 177 disposed to be placed in mesh with the pinion 170 of the shaft 168, the respective pinions 172 and 177 being disposed to be operated alternately to cause the desired shifting of the ribbon as is usual in type writing machines. The upper reel 179 is carried by the shaft 178 and is constructed similarly to the 110 reel 174.

In order to provide a means for shifting the shaft 168 so that the ribbon is continuously fed and reversed according to the positioning thereof upon the respective reels 174 and 179, there are two forked ends 181 125 and 182 of the two respective levers 183 and 184; each of these levers actuating its respective valve 185 and 186 which controls the motors 189 and 190 each actuating a shifting arm 191 which is disposed in op- 130

erable relation to the spool 192 mounted upon and carried by the shaft 168.

Each of the respective valves 185 and 186 is provided with a port 187, which is disposed at the proper time due to the engagement of the pin 181 with one of the levers 183-184, to move the valve to assume the position as shown at the top of Fig. 27, and in registration with the two oppositely disposed ports 188 and 188', which are connected to the vacuum chamber 12 and to the motor chambers 189 and 190, in the present instance the motor 189 being actuated to properly elevate the shaft 168 to disengage the gears 171-172 and engage the gears 170 and 177 to cause the ribbon to be fed from the reel 174 upon the reel 179, the parts being in the position they assume at the initial registration of the port 187 of the valve 186.

The ribbon as clearly shown in Figs. 1, 3, 4 and 10 is guided through the stationary guides 192 carried by the frame of the machine or the stationary portion of the type basket support, the same presenting the ribbon to all of the four type as illustrated in Fig. 12 so that four type may be printed simultaneously upon the surface of the paper carried by the platen 13, and in such a manner that the gear 164 is placed in mesh with the gear 77 which is the main operating gear, as clearly shown in Fig. 11 for the rotation of the platen 13, the dial 202 and the tabulator device 204, and also the ribbon feed mechanism through the sprocket or pulley 167.

Marginal stop and tabulator device.—In order that the platen 13 may be stopped at any position throughout the line, as for plain writing, as regulating the margin, or as in tabulating for bills and the like, a gear 203 forms an inter-linking or connecting means between the gear 201, the dial 202 and the gear 204 keyed upon and rotating the shaft 205, this shaft 205 having keyed upon its upper end, the marginal disk 206, clearly shown in detail in Fig. 24. This disk is provided with the main marginal or fixed stop 207, and the two adjustable marginal stops 208 and 209, the same being adjustably connected for attachment to the periphery of the disk 206, so that, as will presently appear, the plates may be stopped through the respective train of gears at any desired point.

The means for ordinarily stopping and releasing the platen 13 at the beginning and end of a line, comprising either one of the adjustable stops 208-209 and the fixed stop 207, in combination, with the pivoted motor control and signaling lever 214, which is disposed to project between the open spaced ends of the open ring 210 which is permitted a slight sliding movement and constitutes the tabulator stop carrying device. The sig-

naling lever 214 is pivoted at 215 and has its terminal carrying the valve 217 disposed within the valve casing 216, the same being operably connected with the motor 274, and the vacuum chamber 12 so that when the stop 208 engages the outer end of the valve actuating lever 214, the valve will move to open the port and permit of the actuation of the wrist tapping lever 273 (Fig. 3) to signal the operator that the marginal stop 220, must be operated to release the platen. The stop 220 is mounted in the two lugs 219 carried by the open ring 210, as clearly shown in detail in Figs. 24 and 25. This stop 220 is provided with the long end 221 and with the short end 222 so that the short end will engage the stop 208 during the rotation of the disk 206 in the direction of the arrow Fig. 24, after the engagement of the same stop 208 with the signal actuating member 214, and the manipulation of a key to cause the actuation of the motor 228 through the link 223 which causes the marginal stop 220 to disengage the arm 222 from the marginal stop 207 to place the long end 221 in the path to engage the stop 209 and thus lock the platen 13 at the beginning of a new line and simultaneously with the spacing of the carriage to present a new line in type presentation position.

In order to provide a cushioning means for the oscillatory ring 210 when the stops 208 and 209 are in engagement with the pivoted stop 220, the end 211 which is formed in the shape of a plunger and enters the air cushion 212, a slight vent aperture 213 being provided to permit the escape of the air and thus provide a pneumatic buffer for the platen when the stops 208 and 209 have been placed in engagement with the finger 221 of the pivoted stop 220.

In order to provide a means for presenting the platen 13 for tabulating purposes, a plurality of pivoted stops 225 are disposed, as shown in Fig. 24, upon the ring 210 and have their stop engaging ends 226 disposed to engage the stop 207, the motor 228 in each of the respective stops 225 being provided and being operably connected thereto through the link 227 as clearly shown in Fig. 10. These motors 228 are controlled through any of the desired selectors 20, 20', 20^a or 20^b and the necessary key of the machine.

Type basket actuating mechanism.—As clearly shown in Figs. 10 and 12, the section A of the type basket is mounted for sliding movement with relation to the other sections, the reason being that the respective type bars 14 thereof are each provided with three separate type, as clearly shown in Fig. 28, and thus being shiftable to present a single type, at a time in type presentation position relatively to the platen. This case of type bars is therefore carried by the

sliding plate or frame 229, whose upper and lower edges respectively are supported between the anti-frictional rollers 230, there being four in this instance, while connected to and carried by the plate or frame 229 and projecting from one side thereof are the two pins 231 and 232.

Under ordinary conditions, the spring S holds the plate or frame 229 and consequently the case of type bars A in the separated position, so that the small letter will be presented when the keys for actuating these type are operated, but should it be desired to present a capital letter, which is the intermediate type upon the respective type bar, a key is actuated and through the selector 20^a, operates the motor 235, whose movable terminal 233 engages the pin 231 and moves the frame 229 and the type toward the center of the machine so that the capital letter will be propelled against the platen.

Should it be desired to place the third character or the one to the extreme left, as shown in Fig. 28, to the platen, the motor 236 is controlled in a similar manner through the selector 20^a so as to actuate the movable terminal 234, which engages the pin 232, and as the motor 236 is of a greater magnitude and has a greater movement than the motor 235, the frame 229 and the section A carried thereby may be moved a greater distance or one space farther toward the center of the machine. Upon the release of the type, the spring S will return the frame 229 to its initial position as shown in Fig. 10.

Signal device.—In a machine of this character, it is desirable that no audible signal be provided, therefore in order to notify the operator when the platen is at the end of a line or at the end of a page, some means must be provided to attract his attention so that the proper key may be manipulated for presenting a new line for returning the carriage. This is accomplished by means of the pivoted tapper 273, which is mounted at the forward right hand corner of the casing 1, and in such a position as to tap the right wrist of the operator whose hands being in the proper position for manipulating the keys 39—39' and 39^a with his wrist in proper position for engaging the key 55' will be properly notified that it is time to manipulate the keys for shifting the platen or the carriage as may be necessary. This pivoted tapper 273 is controlled through the motor 274, which is controlled by the pivoted valve actuating means 214 when either one of the stops 209 is placed in engagement therewith, the nipple connections of the valve casing 216 being operably connected to the vacuum chamber 12 and the motor 274, so that the motor 274 is automatically actuated due to the en-

gagement of the stop 209 with the valve actuator 214 when the dial 206 has been rotated to the end of the line. Thus the operator will be notified immediately in ample time to manipulate one of the keys which through any one of the selectors may be properly connected with the motor 228 to be manipulated to release the pivoted marginal catch 220 and thus permit the actuation of the devices for presenting a new line, or as the case may be, a new page.

It is also apparent that two alphabets may be used instead of three full alphabets and a portion of a fourth as herein set forth, and that various other key operated devices may be employed to control the various motors for actuating the type bars, rotating the platen, moving the carriage to and against the spring control therefor, and for actuating the ribbon feed.

What is claimed is:

1. A type writing machine, having a type basket provided with a plurality of sections, one section of which is slidable relatively to the others, and each type bar of which carries a plurality of type, the type bars of the stationary section each having a single type, a set of six keys to each section, and means for operably connecting the keys either one at a time or a combination of keys, to operate a selected type bar.

2. A type writing machine, having a circular type basket, one segment of which is slidable relatively to the other, and each type bar of which carries a plurality of type, the type bars of the stationary section each having a single type, a plurality of sets of keys, and a selecting device interposed between the keys and the type bars whereby the depression of a key or combination of keys will operate a selected type bar of either or both segments.

3. A type writing machine, having a platen, a type basket, one section of which is slidable relatively to the other, and each type bar of which carries a plurality of type, the type bars of the stationary section each having a single type, the type of the respective sections having individual presentation positions to the platen, whereby a type of each section may be presented simultaneously to the platen, keys, a pneumatic motor, a vacuum chamber, a vacuum motor to each type bar, and a plurality of selectors one to each section operably connected to the keys and the vacuum motors, whereby the depression of a key or any combination of keys operates its selector to select a single type bar.

4. A type writer, including a frame, a type bar, a vacuum motor operably connected to the type bar, a vacuum creating motor, a depressible key, and means operably connected to the key and vacuum creating motor for connecting the vacuum motor to

the vacuum creating motor to operate the type bar.

5. A type writer, including a frame, a plurality of pivotally mounted type bars, a vacuum motor operably connected to each type bar, a vacuum creating motor, a plurality of depressible keys, and a selector device operably connected to all of the keys and the vacuum creating motor for connecting a 10 single vacuum motor to the vacuum creating motor to operate a selected type bar.

6. A type writer, including a frame, a plurality of pivoted type bars, a vacuum motor operably connected to each type bar, a 15 vacuum creating motor, a plurality of depressible keys, and a plurality of selectively controlled valves operably connected to the keys, whereby the manipulation of a single key or any combination of keys 20 will operate a valve to connect a single vacuum motor to the vacuum creating motor to operate a selected type bar.

7. A type writing machine, including a frame, a plurality of pivoted type bars, a 25 vacuum motor operably connected to each type bar, a vacuum chamber, a vacuum creating motor operably connected to the vacuum chamber, a plurality of selectively

operated keys, a selector device operably interposed between the vacuum motors and 30 the vacuum chamber and controlled from the keys to cause the selective actuation of a single type bar at a time, said selector including a chamber in communication with the vacuum chamber and provided with a 35 plurality of inlet ports, a plate having a plurality of ports one to each vacuum creating motor in communication with the vacuum motors, and a plurality of ported and individually oscillatory disks interposed between 40 the vacuum chamber and the plate and operably connected to the keys, the positioning of the ports of the oscillatory disks with the inlet ports of the chamber and perforated plate placing the vacuum chamber 45 in communication with an individual motor of a type bar upon the depression of a selected key or any combination of keys to operate a type bar.

In testimony that I claim the foregoing 50 as my own, I have hereto affixed my signature in the presence of two witnesses:

JUAN G. HOLGUIN BURBOA.

Witnesses:

SERAPIO HUERTO,
JOSÉ J. MELÉNDEZ.
